(57) CLAIM

I claim the ornamental design for a sock with arch line detail, as shown and described.

DESCRIPTION

FIG. 1 is a side view of the sock with arch line detail showing my new design;

FIG. 2 is a perspective view thereof; and,

FIG. 3 is a top view thereof.

The broken-line showing of a sock and stacked horizontal lines in FIGS. 1-3 are included for the purpose of showing environmental portions of the sock with arch line detail and form no part of the claimed design.
